STOPPING DEVICE FOR LOOMS
OR THE LIKE

Jack Breen, Towanda, Pa.

Application May 15, 1933, Serial No. 671,098

18 Claims. (Cl. 139—337)

This invention relates to an electrical device for arresting the operation of looms when a harness-cord breaks or slips or when for any cause one or more of the harness-frames fall below the bottom limit of their travel. Obviously, when a harness-frame is completely released, for example, by rupture of a cord, breakage of the warp threads will ensue. If, however, the harness suspension is only disarranged, the displacement may be such as to cause the warp yarns to rub on the shuttle race. When the warp consists of or embodies fine silk or synthetic yarns, such rubbing action will cause chafing and fracture of the fibers of the yarn with resulting faults that are sometimes not discernible until after the cloth has been removed from the loom or the weaving has at least proceeded too far for rectification of the fault. It is an object of the present invention to provide a simple device for the purpose intended, easy to apply to and remove from the loom without protracted interruption in its operation, and which is readily accessible for adjustment.

Further objects of the invention are set forth in the following specification which describes several preferred embodiments of the invention, by way of example, as illustrated by the accompanying drawings. In the drawings:

Fig. 1 is a perspective view of the improved stopping device showing the method of applying it to a loom;

Fig. 2 is a diagrammatic view of the electrical circuit for the device;

Fig. 3 is a detailed front view of a contact-blade and its holder;

Fig. 4 is a front view showing the blade and holder assembled within a carrier;

Fig. 5 is an end view of the same;

Fig. 6 is a front view showing an alternative mounting for the blade;

Fig. 7 is an end view of the mounting illustrated in Fig. 6;

Fig. 8 is a front view of the device showing it applied to a different harness;

Fig. 9 is a detailed view of the spring hook used in connection with the embodiment illustrated in Fig. 8;

Fig. 10 is a perspective view of a modified form of heddle-frame;

Fig. 11 is a front view of an alternative mounting for the contact-blade;

Fig. 12 shows the device removed from the loom and illustrates the method of packing the parts for shipment or storage;

Fig. 13 is a perspective view of a modified form of harness;

Fig. 14 is a detailed view of the rear hanger; and

Fig. 15 is a composite perspective view of the parts of a modified type of supporting means.

Like reference characters indicate the same parts throughout the specification and drawings. In the drawings the arrow *a* designates a direction of view from front to rear of the loom.

The term "stop-motion" is used in a generic sense to denote any form of electrical loom stopping device controlled either by the warp or filling threads, and to include such instrumentalities as are necessary to effect stopping of the loom.

The term "magnet" includes any known electromagnetic device suited for stop-motion service, whether it be used with direct or alternating current.

The term "generator" connotes any source of electrical energy such as a magneto, dynamo, transformer, battery or the like.

The term "distribution system" designates the wiring and connections that connect the generator with the stop-motion instrumentalities.

"Return circuit" defines suitable conductive instrumentalities through which the current, after serving the stop-motion, returns to the generator, and may include brackets, bolts and the loom-frame in which the circuit is usually grounded.

The term "cord" or "harness-cord" connotes harness suspension of any kind.

In Figs. 1 and 8 only one harness *H* is shown, although a plurality of harnesses are usually employed in looms of the present type. Each harness-frame is moved vertically by the pattern mechanism, not shown, through means of harness-cords *4* and *5*. Normally this vertical movement extends between definite prescribed limits and movement beyond such limits is abnormal. The cords *4* and *5* are usually carried over sheaves *6* mounted on the front and rear loom arch-members *7* and *8*. These members are spaced apart sufficiently to accommodate a number of harnesses. As shown in Fig. 10 each harness-frame comprises a wooden top member *9* and a wooden bottom member *10* which are joined together by means of metal end pieces *11*. Extending from end to end of the harness-frame and secured to the metal end pieces *11* is a top heddle-shaft *12* and a bottom heddle-shaft *13* constructed of metal. On these heddle-shafts the heddles *14* are strung in the usual manner.

Extending through the interior of the harness-frames and transversely of the heddle-shafts are two contact units C which are mounted on the loom by suspending them from the arch-members 7 and 8 thereof in the manner as later explained. The contact units comprise metallic blades 15 which are arranged for vertical sliding movement within the sides of a holder or bar 17 and preferably insulated therefrom by a strip 16 of fiber or similar nonconductive material. As both contact units are identical in construction only one will be herein described in detail. The rearward end of the contact-blade 15 projects beyond the holder 17 and the insulator 16 to provide a terminal for receiving an electrical circuit wire 13. As shown in Fig. 3 the holder 17 is formed near its ends with two slots 19 and two recesses 20. The contact-blade 15 together with the insulator 16 and holder 17 are mounted in a metallic carrier 21 which is of channel form in cross-section, the sides of the channel rising above the top edge of the holder 17 but not extending to the level of the top edge of the contact-blade 15, when the latter is in normal raised position.

In the sides of the carrier 21 are two holes 22 which register with the slots 19 in the holder 17. Headed pins 23 and 24 are inserted through the holes 22 and slots 19 to slidably mount the holder 17 in the carrier 21; cotter-pins being used to prevent axial displacement of the pins. Springs 26 positioned in the recesses 20 of the holder 17 and bearing against the bottom of the carrier 21 act to maintain the holder 17 elevated with the top edge of the blade 15 above the level of the top edges 27 of the carrier 21 as above described. The front pin 23 is longer than the rear pin 24 to provide that it may pass through an angle piece 28 which supports the carrier 21 and its attached holder 17 and blade 15. The angle piece 28 is fastened to the bottom of a front hanger 29 which is secured at its upper end to a depending extension 30 of a bracket 31 by means of a bolt 32 and a thumb-nut 33. The bracket 31 is secured to the front arch 7 of the loom by a pair of bolts 34 and a clamping plate 35.

The rearward end of the carrier 21 is secured to a rear hanger 36 by a clamp-plate 37 and a bolt 38. The rear hanger 36 is offset at 39 by nearly the thickness of the carrier 21 so that by tightening the bolt 38 the plate 37 is clamped to the carrier. This fastening means provides for adjustment when the device is used with looms of different types and sizes wherein various forms of harness equipment are employed. The rear hanger 36 is supported from the rear arch 8 by a bracket 31 and plate 35 similar in construction to those already described.

The depending extension 30 of each bracket 31 is formed with serrations or corrugations 40 on its inner face against which the top of the hanger is secured. The top inner sides of the front and rear hangers 29 and 36 are formed with similar serrations or corrugations 41 adapted to be clamped against the serrations 40 of the brackets 31. The serrations 40 and 41 are of equal pitch and of sufficiently close spacing to permit fine adjustment in the height of the contact-blades 15 to provide for proper cooperation with the heddle-shafts. As shown in Figs. 1, 2 and 8, the circuit closing units comprising the contact-blades 15 and their holders 21 are located slightly below the top heddle-shaft 12 with which they coact. To effect vertical adjustment of the contact units the front and rear hangers 29 and 36

are provided with slots 43 and 44 in their serrated upper ends through which the bolts 32 extend. The interlocked serrated surfaces not only provide for vertical adjustment of the units but also serve as a locking means to insure against turning and displacement thereof.

The contact units are connected in an electrical circuit in the manner as next explained. From one pole of the generator 45 a distribution system 46 runs through a switch 48 to the magnet 47 of the stop-motion of the loom. From the magnet 47 the circuit wire 18, previously mentioned, extends to the contact-blade 15 which forms a terminal for the distribution system 46. The return wire 49 extends from the metallic holder 21 of the contact unit to the other pole of the generator to complete the circuit. In the event of breakage or disarrangement of any part of the harness suspension means such as one of the cords 4 or 5, the harness-frame falls below its normal operating position. When the harness-frame descends its top heddle-shaft 12 encounters the contact-blade 15 and pushes the latter downwardly within the carrier 21. As the blade 15 is slid downwardly against the action of the springs 26 the shaft 12 also encounters the top edges of the carrier 21 thus permitting the current to pass between the blade 15 and the carrier. With the circuit thus closed the magnet 46 is energized to operate suitable instrumentalities, well known to those versed in the art, which act to stop the loom or other apparatus.

The foregoing description constitutes one embodiment of the invention but various modifications, to be next described, may be made in the construction thereof. Figs. 6 and 7 show an alternative construction in which the blade 50, which corresponds to the blade 15 above described, is embedded or moulded in a holder 51 constructed of suitable insulation material. The non-conductive holder 51 has two slots 52 corresponding to the slots 19 and recesses 53 corresponding to the recesses before described. In this particular embodiment the insulation strip 16 is eliminated.

In some instances the harness-frames are raised through means of the straps or cords and are returned downwardly by springs 54 shown in Fig. 8. The harness-springs 54 are usually anchored to a spider-member 55 which in turn is secured to the loom-frame 56 to which the stop-motion return circuit is grounded. As in the first described construction when the harness drops the top shaft 12 encounters the contact-blade 57 which is mounted in the metallic body or holder 58 of Fig. 11. The blade 57 is insulated from the holder by means of a strip 59. In this construction, the blade need not yield and descend when hit or encountered by the top shaft 12 of a descending harness-frame. The top and bottom shafts 12 and 13 are secured to the metal end members 11 of the harness-frame H so that they are metallically and therefore electrically connected. The bottom shaft 13 is connected to the springs 54 by means of a hook 61 shown in detail in Fig. 9. The shank 60 of the hook 61 is preferably slotted to receive the bottom shaft or bar 13 which is forced into the slot. The manner of suspending the contact-blade 57 is the same as previously explained. The front end of the holder 58 is secured by means of the pin 23 to the angle piece 28 of the front hanger 29 which in turn is secured to the bracket 31. The rear hanger 62 is attached to the holder 58 by the bolt 63 and thumb-nut 64, see Fig. 8. As shown in Fig. 11 the holder 58 has an elongated slot 65 through which

the bolt 63 extends whereby to permit the rear hanger 62 to be adjusted along the holder to adapt it for use with various size looms.

In this modified form of device the distribution system 45 from the generator is connected to the projecting rear extremity of the contact-blade 57 while the return circuit extends from the generator to the loom-frame in which it is grounded. From the grounding point the current passes through the loom-frame 56, spider 55, springs 54, hook 61, bottom heddle-shaft 13, harness end members 11 to the top shaft 12 which forms a terminal of the return circuit. When the harness-frame is in normal suspension, the top shaft 12 does not reach and encounter the contact-blade 57, but when the harness-frame has been lowered from its normal position by the yielding of a strap or otherwise, the top shaft 12 encounters the contact-blade 57. The blade 57 being the terminal of the same circuit but of opposite polarity, the circuit is thus closed and the magnet 47 is energized to effect stopping of the loom.

Referring now to Fig. 13, in place of the heddle-shaft 12 a separate metal contact-bar 66 extending from end to end of the harness-frame may be used with equal success.

In place of using an elongated hook 61 with a split shank, the metal end member 11 of the harness-frame H may be extended along the bottom of the lower harness-frame member 10 in the manner as illustrated in Fig. 10 and the spring hook secured directly to it.

Fig. 15 shows a modified form of suspension means for use on looms wherein the contact units C are not suspended from the arch-members. A bracket 70 is mounted on each side frame of the loom being attached thereto either directly or through the means of separate brackets or parts secured to the loom side as for example the bracket which carries the arch. The bracket 70 has a toothed or corrugated area 71 which is provided with a bolt slot 72. A second bracket 73 also having corrugations 74 and a slot 75 is secured to the bracket 70 by means of a bolt 76 and a nut 77; the bolt 76 passing through the slots 72 and 75 to permit vertical adjustment of the bracket 73. The bracket 73 is provided at one end with a seat 78 against which an arm 80 is secured by means of a bolt 82. Extending rearwardly from the bracket 73 is an arm 79. Both arms 80 and 79 have apertures for receiving bolts 81 and 83 which secure the contact unit C thereto. The contact unit of this construction is preferably the same as that shown in Fig. 11 in which the blade is carried in a metal holder.

Either of the general constructions above described provides an attachment that can be compacted into a small space for shipment or storage. Referring to Fig. 12 the contact unit C comprising the blade and connected parts shown in Figs. 3, 6, 11 or 15 may be folded back upon the front hanger 28 by swinging them on the pin 23. The rear hanger may be placed alongside the contact units and all the parts wrapped up together. When attaching the device to a loom it is necessary only to swing the contact unit open from its hanger, pass its free end through the harness and clamp the suspension bracket in place on the arch. The rear hanger is then mounted on the arch and the contact unit attached to the rear hanger, after which the contact unit may be adjusted to its proper height. The attachment of the parts in this manner thus requires but a brief stopping of the loom. Moreover, the height of the contact unit is such as to permit ready in-

spection for setting, and adjustment may be made while the loom is in operation.

While I have herein shown and described the improved device as embodied in several preferred forms of construction, it is to be understood that further modifications may be made in the structure and arrangement of its parts which would fall within the spirit or scope of the invention. Therefore, without limiting myself in this respect, I claim:

1. In a stop-device for looms, the combination of an electrical stop-motion, an electrical circuit therefor, a heddle-shaft for the loom harness constituted as a conductor, electrical connections between the heddle-shaft and one side of the electrical circuit, and an immovable electrical terminal connected with the other side of the circuit and extending through the harness transversely of and below said heddle-shaft to intercept the latter in its downward movement, said heddle-shaft and terminal making electrical contact to close the circuit when such interception occurs to cause actuation of the stop-motion to arrest the operation of the loom.

2. In a device for stopping a loom through improper positioning of a harness-frame, the combination with the harness-frame and heddle-shafts therefor, of an electrical stop-motion, an electrical circuit for the stop-motion, a stationary electrical contact-member extending through said harness-frame below the heddle-shafts from front to back of the loom, means to support the forward end of the contact-member in position to intercept the heddle-shaft of the front harness in case of excessive descent of the latter, means to support the rearward end of the contact-member in a position to intercept the heddle-shaft of the rearmost harness-frame and of other harness-frames in case of excessive descent by any of them, means to connect the contact-member with one side of the electrical circuit, and means to connect the heddle-shafts with the opposite side of the circuit.

3. In a device for stopping a loom, the combination with a harness-frame thereof and the heddle-shaft therefor, of an electrical stop-motion, an electrical circuit for said stop-motion, an electrical contact-member mounted transversely of the heddle-shaft below its normal limit of descent, means adjustable to mount the ends of said contact-member at different heights, and means for connecting the contact-member and heddle-shafts with opposite sides of the electrical circuit whereby encounter of the heddle-shaft with the contact-member by descent of the harness-frame beyond its normal limit will close the circuit through said heddle-shaft to cause action of the stop-motion.

4. In a device for stopping a loom, the combination with a plurality of harness-frames each having a heddle-shaft, of an electrical stop-motion for the loom, an electrical circuit therefor, a contact-member extending through all the harness-frames from front to back of the loom transversely of and below the heddle-shafts, adjustable suspension means to support the forward end of the contact-member, adjustable suspension means to support the rearward end of said contact-member, said adjustable suspension means cooperating to locate the contact-member in close proximity to the lower limit of normal movement of each of the heddle-shafts, means to connect the contact-member with one side of the electrical circuit, and means to connect each heddle-shaft with the opposite side of the circuit.

whereby closing of the electrical circuit is effected through any heddle-shaft that encounters the contact-member by reason of its harness-frame descending below its normal limit of movement.

5. In a stop-device for looms, the combination with a harness, heddle-shafts carried by the harness, means to move the harness within a normal range of movement, and a usual electrical stop-motion, of a channel-shaped carrier, a contact-bar within the carrier, insulation for the contact-bar, means to mount the contact-bar for vertical movement relative to the carrier, springs to impart such vertical movement to the contact-bar 10 to maintain its top edge normally above the top edges of the carrier, means to mount the carrier and contact-bar within the harness and adjacent the station of the heddle-shafts at one normal extreme of movement to be encountered by said shafts when the latter are moved beyond their 15 normal range, and circuit connections to connect the contact-bar with the electrical stop-motion.

6. In a device for stopping a loom through improper positioning of a harness-frame, the combination with the harness-frame, its heddle-shaft, a stop-motion, distributing system and return circuit for said stop-motion, of a contact-member extending through said harness-frame transversely of the heddle-shaft and in position 20 to be encountered by said heddle-shaft when the latter is carried beyond the normal extreme of its movement, means to electrically connect the contact-member with the distributing system, and means to connect the heddle-shaft with the 25 return circuit.

7. In a device for stopping a loom when a harness-frame travels beyond the normal extreme of its path of movement, the combination with a stop-motion, a harness-frame and heddle-shaft carried by said frame, of a contact-blade, insulation within which said blade is mounted, elastic support to hold the blade in position to encounter the heddle-shaft should said shaft travel beyond its normal path and permit the blade to yield 40 upon such encounter, a circuit wire to connect the blade with the stop-motion, a carrier by which the blade and insulation and elastic support are mounted on the loom-frame, and means to mount the carrier on the loom-frame in electrical contact therewith.

8. In a stop-device for looms, the combination with a harness, heddle-shafts carried by the harness, means to move the harness within a normal range of movement and a usual electrical stop-motion, of a carrier, means to mount the carrier within and transversely of the harness adjacent the heddle-shafts' extreme range of movement to be encountered by any heddle-shaft that moves beyond its normal range, a contact-bar 50 vertically movable with respect to said carrier, means to mount the contact-bar on the carrier, springs to impart vertical movement to raise the top edge of the contact-bar above the top edge of the carrier, and circuit connections connecting said contact-bar with the electrical stopping agency.

9. In a device for stopping a loom, the combination with a plurality of harness-frames and heddle-shafts carried thereby, of an immovable contact-blade extending through said frames transversely of said shafts in position to be engaged thereby when the harness-frames descend beyond their normal limit, a stop-motion, and an electrical circuit including the blade and the stop-motion, said electrical stop-motion circuit being

closed by engagement of the blade with a heddle-shaft.

10. In a device for stopping a loom when a harness-frame is out of vertical placement, the combination with a heddle-shaft in said frame, of an immovable contact-blade extending through said frame transversely of and outside the normal range of movement of the shaft, insulation for said blade, and means to mount the insulated blade in the loom, of a stop-motion, a 10 return circuit therefor, a source of electrical current for the circuit, a circuit wire connecting the blade with said stop-motion, and means to connect the blade with the return circuit thereof whereby contact of the shaft with the blade acts 15 to close the circuit and actuate said stop-motion.

11. In a device for stopping a loom, the combination with a loom-harness, heddle-shafts, a stop-motion, its distributing system, its return circuit and the loom-frame in which the return 20 circuit is grounded, of a U-shaped carrier, an insulated blade within the carrier and movable vertically with respect to said carrier, insulation for the blade, means to hold the blade to the carrier and limit its movement, springs to lift and 25 normally maintain the blade elevated, means to mount the carrier on the loom-frame and in electrical connection therewith, means for supporting said blade in proximity to the normal extreme of travel of said heddle-shafts, and a 30 circuit wire connecting said blade with the stop-motion.

12. In a device for stopping a loom, the combination with a harness-frame, heddle-shafts carried thereby, a stop-motion, a distribution 35 system and return circuit, of a U-shaped carrier 21, a blade within the carrier, an insulated holder 17 for the blade formed with transverse slots 19 and recesses 20, pins extending through the carrier and the slots in the holder, springs within the 40 recesses and reacting against the carrier to raise the holder and blade, a circuit wire to connect the blade with the stop-motion circuit, and means to mount the carrier on the loom in connection with the return circuit of the stop-motion.

13. In an electrical device for stopping looms through derangement of a harness-frame, the combination with a harness-frame, a heddle-shaft and means to suspend them, of an immovable electrical terminal extending through and 50 transversely of said harness-frame out of contact with said shaft, means to mount said terminal, a stop-motion magnet, a generator, a circuit connecting the terminal and magnet in series with one pole of the generator, and connections 55 between the other pole of the generator and the heddle-shaft.

14. The combination with the electric circuit of a loom stop-motion, a plurality of heddle-shafts, harness-frames to carry said heddle-shafts, suspension devices for said harness-frames, and means to connect said heddle-shafts with one side of the stop-motion circuit, of immovable terminals for the other side of said circuit near each end of the harness-frames, each terminal extending through all the harness-frames transversely of and below the aforesaid heddle-shafts, and means to mount said terminals adjustably with respect to said heddle-shafts.

15. In an electrical device for stopping looms 70 when a harness-frame drops, the combination with a loom, its arch, harness-frames, heddle-shafts, means for operatively suspending the harness-frames and shafts, a generator and circuit connections connecting the heddle-shafts with 75

- one pole of the generator, a magnet, circuit connections to connect the magnet to the other pole of the energy source, of a stationary circuit terminal connected in series with the magnet and 5 extending through the harness-frames and below the shafts, a circuit wire to connect said terminal and magnet, a bracket to suspend the stationary terminal mounted on the loom arch, means to secure the bracket to the arch, hangers 10 adjustably mounted on said bracket, said hangers being secured to the stationary terminal, and means to secure the hangers to the aforesaid bracket in adjusted position.
16. In a device for stopping a loom upon occurrence of a default of the harness suspension, the 15 combination with the loom arch-members, harness-frames, heddle-shafts carried by the harness-frames, suspension devices for the harness, a stop-motion, contact-members extending 20 through the harness-frames and below the heddle-shafts, a stop-motion and circuit wires connecting the contact-members with the stop-motion, of brackets mounted on the arch-members, hangers adjustable on said brackets, means to secure said hangers and brackets in adjusted position, means to mount the contact-members on the hangers, and insulation between the contact-members and said mountings.
17. In a device for stopping a loom upon default of the harness suspension, the combination 25 with a front arch-member, a rear arch-member, harness-frames, heddle-shafts carried by said harness-frames, suspension devices for the harness, a stop-motion, contact-members extending 30 through the harness-frames and transversely of

and below the heddle-shafts, a stop-motion and circuit wires connecting the contact-members with the stop-motion, of brackets mounted on the front arch-member, hangers adjustably secured to said brackets, means to secure the hangers to said brackets, a hinge connection for securing the contact-members to said front hangers, brackets mounted on the rear arch-member, rear hangers adjustably secured to said brackets, bolts to secure said rear hangers to their brackets, 10 means to attach the rear hanger to the contact-member at different points lengthwise of the latter, insulation for the contact-members, and circuit wires to connect the contact-members with the stop-motion.

18. In an electric device for stopping a loom through disarrangement of a harness-frame, the combination with the harness-frame, an electrically conductive member mounted within and carried by said frame and extending longitudinally thereof, and means to suspend said frame and member, of an immovable contact-member extending through and transversely of said harness-frame and out of contact with the contact member carried thereby when the harness-frame is in 25 normal arrangement but caused to contact with said member through disarrangement of said harness-frame, means to adjust said contact-member in such relation, a stop-motion, a generator therefor, a circuit wire connecting the 30 contact-member with the stop-motion, and means to connect the contact member within the harness-frame with said generator.
